US0D1100884S

(12) **United States Design Patent** (10) Patent No.: **US D1,100,884 S**
(45) Date of Patent: ** *Nov. 4, 2025

(54) **HORIZONTAL STAND FOR A VIDEO GAME CONSOLE**

(71) Applicants: **ESSENCE TECHNOLOGY HOLDINGS (HK) LIMITED**, Hong Kong (CN); **NEXIGHT INC**, Beaverton, OR (US)

(72) Inventor: **Dongwei Yang**, Hong Kong (CN)

(73) Assignees: **ESSENCE TECHNOLOGY HOLDINGS (HK) LIMITED**, Hong Kong (CN); **NEXIGHT INC**, Beaverton, OR (US)

(*) Notice: This patent is subject to a terminal disclaimer.

(**) Term: **15 Years**

(21) Appl. No.: **29/828,014**

(22) Filed: **Feb. 23, 2022**

(30) **Foreign Application Priority Data**

Jan. 19, 2022 (CN) 202230035470.7

CLAIM

The ornamental design for a horizontal stand for video game console as shown and described.

DESCRIPTION

FIG. 1 is a perspective view of a first embodiment of a horizontal stand for video game console showing my new design;

FIG. 2 is another perspective view thereof;

FIG. 3 is a perspective view thereof in a configuration of use;

FIG. 4 is an exploded perspective view thereof in the configuration of use;

FIG. 5 is a perspective view of a first component of the first embodiment of the horizontal stand for video game console shown separately for ease of illustration;

FIG. 6 is another perspective view thereof;

FIG. 7 is an enlarged front elevational view thereof;

FIG. 8 is an enlarged rear elevational view thereof;

FIG. 9 is a left side elevational view thereof;

FIG. 10 is a right side elevational view thereof;

FIG. 11 is a top plan view thereof;

FIG. 12 is a bottom plan view thereof;

FIG. 13 is a perspective view of a second component of the horizontal stand for video game console shown separately for ease of illustration;

FIG. 14 is another perspective view thereof;

FIG. 15 is an enlarged front elevational view thereof;

FIG. 16 is an enlarged rear elevational view thereof;

FIG. 17 is a left side elevational view thereof;

FIG. 18 is a right side elevational view thereof;

FIG. 19 is a top plan view thereof;

FIG. 20 is a bottom plan view thereof;
FIG. 21 is a perspective view of a second embodiment of the horizontal stand for video game console;
FIG. 22 is another perspective view thereof;
FIG. 23 is a perspective view thereof in a uconfiguration of use;
FIG. 24 is an exploded perspective view thereof in the configuration of use;
FIG. 25 is a perspective view of a first component of the second embodiment of the horizontal stand for video game console shown separately for ease of illustration;
FIG. 26 is another perspective view thereof;
FIG. 27 is an enlarged front elevational view thereof;
FIG. 28 is an enlarged rear elevational view thereof;
FIG. 29 is a left side elevational view thereof;
FIG. 30 is a right side elevational view thereof;
FIG. 31 is a top plan view thereof;
FIG. 32 is a bottom plan view thereof;
FIG. 33 is a perspective view of a second component of the second embodiment of the horizontal stand for video game console shown separately for ease of illustration;
FIG. 34 is another perspective view thereof;
FIG. 35 is an enlarged front elevational view thereof;
FIG. 36 is an enlarged rear elevational view thereof;
FIG. 37 is a left side elevational view thereof;
FIG. 38 is a right side elevational view thereof;
FIG. 39 is a top plan view thereof; and,
FIG. 40 is a bottom plan view thereof.

The broken lines in the drawings depict portions of the horizontal stand for video game console that form no part of the claimed design.
